United States Patent Office.

HENRY W. MINNEMEYER, OF ALLEGHENY CITY, PENNSYLVANIA.

Design No. 4,353, dated September 13, 1870.

DESIGN FOR A BREAST-SLIDE FOR HARNESS.

The Schedule referred to in these Letters Patent and making part of the same.

To all whom it may concern:

Be it known that I, HENRY W. MINNEMEYER, of the city and county of Allegheny and State of Pennsylvania, have invented and produced a new and original Design for a Breast-Slide for Harness, of which the following is a specification.

The nature of my design is fully shown in the accompanying drawing, to which reference is made.

Figure 1 is a perspective view of my design for a breast-strap slide for harness.

Figure 2 is a vertical and longitudinal section of the same, representing the position of the breast with relation to the slide.

A represents frame of the slide.

B B represent the openings in the frame for the breast-strap.

D D represent the sides of the frame.

C represents a friction-roller.

e represents the axis of the friction-roller.

The advantage of my design and form of slide for breast-strap for harness consists in the facility it affords the manufacturer in constructing it.

Having thus described the nature of my design,

What I claim as my invention is—

The design for a breast-strap slide, as described and shown in the accompanying drawing.

H. W. MINNEMEYER.
